US00D457114S

(12) **United States Design Patent** (10) Patent No.: **US D457,114 S**
(45) Date of Patent: **** May 14, 2002**

(54) **MIRROR ASSEMBLY**

(75) Inventors: **Heinrich Lang**, Ergersheim (DE);
Alexander Stenzel, Columbia, SC (US)

(73) Assignee: **Lang-Mekra North America, LLC**,
Ridgeway, SC (US)

(**) Term: **14 Years**

(21) Appl. No.: **29/136,036**

(22) Filed: **Jan. 24, 2001**

Related U.S. Application Data

(63) Continuation of application No. 29/110,447, filed on Sep. 7, 1999, now abandoned.

(51) **LOC (7) Cl.** **12-16**

(52) **U.S. Cl.** **D12/187; D12/188**

CLAIM

The ornamental design for a mirror assembly, as shown and described.

DESCRIPTION

FIG. 1 is a front perspective view of a mirror assembly according to the present design;

FIG. 2 is a left side perspective view thereof;

FIG. 3 is a front view thereof;

FIG. 4 is a left side view thereof;

FIG. 5 is a right side view thereof;

FIG. 6 is a rear view thereof;

FIG. 7 is a top view thereof;

FIG. 8 is a bottom view thereof; and,

FIG. 9 is a left side perspective view of a mirror assembly showing a second embodiment of our new design, it being understood that the sole difference is the inclusion of an antenna mount; all remaining views being the same as the first embodiment as shown in FIGS. 1-8.
